(57) **CLAIM**

The ornamental design for a clothes bar, as shown and described.

DESCRIPTION

FIG. 1 is a perspective view of the clothes bar, showing a new ornamental design therefor;

FIG. 2 is a right side elevational view thereof;

FIG. 3 is a top plan view thereof;

FIG. 4 is a left side elevational view thereof;

FIG. 5 is a bottom plan view thereof; and,

FIG. 6 is an elevational view of one thereof, the other end being the same.

For ease of illustration, the break in the elongated portion of FIGS. 2-5 represents indeterminate length.
